UNITED STATES PATENT OFFICE.

EDWARD STERN, OF PHILADELPHIA, PENNSYLVANIA.

INK-WELL.

SPECIFICATION forming part of Letters Patent No. 532,347, dated January 8, 1895.

Application filed April 4, 1892. Serial No. 427,731. (No model.)

To all whom it may concern:

Be it known that I, EDWARD STERN, a citizen of the United States, and a resident of Philadelphia, Pennsylvania, have invented 5 certain Improvements in Ink-Well, of which the following is a specification.

The object of my invention is to construct an ink well of the barometer type, in which the dipping pit section is independent of, and 10 detachable from the body of the well, a further object of my invention being to construct the dipping pit section in such a manner that a small quantity of ink is exposed to the air, and in which a pen can be readily charged 15 with ink, as more fully described hereinafter, reference being had to the accompanying drawings, in which—

Figure 1, is a sectional view of my improved ink well showing the pen in position. Fig. 2, 20 is a face view of the ink well with the dipping pit section removed. Fig. 3, is a perspective view of the dipping pit section detached from the well. Fig. 4, is a plan view. Fig. 5, is a section on the line 1—2, Fig. 1; and Fig. 6, is 25 a section on the line 3—4, Fig. 1.

In the manufacture of ink wells of the type shown, it has been the custom to make the dipping pit section a permanent part of the body of the well, and have a comparatively 30 large passage uniting the ink reservoir with the dipping pit section. Dipping pit sections of this character expose a greater quantity of ink than is absolutely necessary, and to properly clean these wells, the ink both in the dipping pit and in the reservoir, has first to be removed. Another objection to these wells is 35 that they are hard to fill, being filled from the dipping pit. I overcome these objections, and secure many desirable results, in the following manner:

A is the body of the well, made of glass or other suitable material, and is preferably molded and shaped by a plunger passing into the body of the well from the front forming 45 the ink reservoir, and the front of this reservoir is partially closed and formed into a neck a, as shown in Figs. 1 and 2. The mouth a' in the neck a is preferably on a line with the base line of the reservoir, and it will be noticed that the reservoir formed by the plunger is preferably tapered, not only to allow 50 for the ready removal of the plunger, but also

to allow the sediment that naturally collects in the reservoir to be carried forward to the mouth a'. 55

On the top of the well are pen racks, although these racks may be dispensed with in some instances, and the exterior shape of the well may be readily changed, and the reservoir formed by the plunger may, in some instances, be square, but I prefer the shape shown. 60

Adapted to the mouth a' of the body is a dipping pit section B, having an extension b on which is mounted a cork or packing ring 65 c, preferably cast upon the extension. This cork or packing ring is made of rubber, or other suitable material, and when the dipping pit section is forced into position, the rubber makes a tight joint between the body and the 70 dipping pit.

The exterior of the dipping pit section can be of any ornamental shape required, and is provided with a suitable lid E, which is pivoted at e to the rear of the dipping pit section. 75

d is the dipping pit proper, and is shaped as clearly shown in Figs. 1 and 5, and is of sufficient diameter to accommodate an ordinary pen. 80

The inlet f from the reservoir to the dipping pit d, is in the center of the extension b, and is diminished in size at the forward end so as to allow for a very small opening into the dipping pit, and as the normal level of 85 the ink in this dipping pit is on a line with this opening, only a very small quantity of ink is exposed, and it will be noticed on referring to Fig. 1, that as the passage f is above the bottom of the reservoir, any sediment 90 which may accumulate in the reservoir, will be collected below the line of the passage f, thus preventing the sediment from passing into the dipping pit. If however, sediment does collect in the dipping pit d owing to exposure, this dipping pit can be readily cleaned by simply turning the ink well upside down, and throwing the ink out of the dipping pit, as it will not flow back into the reservoir owing to the contraction of the passage f. Thus, 95 it will be seen that the dipping pit while holding a small quantity of ink, can be readily cleaned without cleaning the whole of the well. The passage f is contracted in such

manner as will permit the free entrance of air into the reservoir without the air opposing the outward flow of ink, as the bubbles of air once past the contracted portion of the 5 passage will rise to the top of the passage and pass onward into the main reservoir, taking the place of the ink which flows from it into the dipping pit as use is made of the well.

It will be noticed that the dipping pit increases in diameter as it nears the top. This 10 allows for the ready insertion of the pen into the pit, and also provides space for ink upon expansion of air or ink within reservoir.

Preferably on the wall of the body opposite 15 the passage *f*, is formed a projection or rib *g*, which, when the pen is inserted into the pit, as shown in Fig. 1, projects into the hollow space of the pen. This rib, in conjunction with the pen, facilitates capillary attraction, 20 and aids the ink to ascend upon the pen higher than the level of the ink in the pit. This rib may in some cases, extend up farther than in others, and may conform more closely to the shape of the pen, but a rib as 25 shown in Fig. 1, will be sufficient for the majority of pens.

On the upper edge of the dipping pit is a stop *h*, against which the pen holder strikes when the pen is inserted into the dip the full 30 distance. This stop is so arranged as to prevent the pen from striking the bottom of the pit.

Surrounding the dipping pit proper, is an 35 overflow space *d'*, which receives the ink when owing to certain conditions, the ink is raised to such an extent as to overflow the pit.

It will be noticed that the dipping pit is inclined to about the natural angle at which the pen is dipped, so that the pen can be 40 readily inserted. It will also be noticed that instead of the extension *b* having a cork or packing on its exterior, it may be increased in diameter, and the packing or cork inserted between the outside of the neck of the body 45 of the well, and the inside of the extension *b*, but I prefer to make the well as shown in Fig. 1, which enables me to make, in many instances, the body portion of glass, and the dipping pit portion of metal, rubber or glass, 50 which can be readily attached to or removed from the body of the well, and being at the side, is in proper position to be used, and by

simply turning the well on end, the dipping pit portion can be removed from the body, and the well cleaned. The construction of 55 the dipping pit portion facilitates its cleaning. Thus an ink well of this construction is readily made, the body portion being molded and shaped as desired, and can be made complete by a glass manufacturer, while the dipping pit portion is entirely independent and 60 free from the body, and can be made by a manufacturer of metal, rubber or other goods, and this portion of the well, can be in fact, highly ornamented, and made of precious metals, giving a neat appearance to the article. 65

The lid *E* can be readily attached to, or removed from the dipping pit portion, by simply spreading the flanges, and allowing the pins, which are preferably carried by the lid, 70 to spring.

The shape and size of the dipping pit proper can be altered to suit different styles of pens, or one or more dipping pits of different shapes and sizes can be attached to each 75 well, if desired.

I claim as my invention—

1. The combination in an ink well of the barometer type having a reservoir therein, an opening into said reservoir at the front side, 80 the bottom of said reservoir being inclined from the back to the front, and in line with the bottom of said opening, and a removable dipping pit section adapted to said opening, substantially as described. 85

2. The combination in an ink well of the barometer type, of a fixed reservoir, an opening therein, dipping pit portion adapted to said opening, a dipping pit therein, said dipping pit extending below the passage forming a communication between the dipping pit and the reservoir, with a vertical rib extending into the dipping pit opposite the passage so as to conform to the shape of the pen and thus facilitate the capillary action, substantially as described. 95

In testimony whereof I have signed my name to this specification in the presence of two subscribing witnesses.

EDWARD STERN.
